CLAIM

The ornamental design for the manifold for an irrigation or aspiration instrument, as shown and described.

DESCRIPTION

FIG. 1 is a front elevational view of a manifold for an irrigation or aspiration instrument showing our new design, the rear elevational being the similar as the front elevational view;

FIG. 2 is a left side elevational view thereof;

FIG. 3 is a right side elevational view thereof;

FIG. 4 is a top plan view thereof; and,

FIG. 5 is a bottom plan view thereof.

The broken lines shown in FIGS. 1-5 represent connections for coupling the device to other components and internal structure of the device, all not being part of the present design patent application.
